UNITED STATES PATENT OFFICE.

ASHER LAMBERT, OF NEWARK, NEW JERSEY.

DERRICK-SWINGING ATTACHMENT FOR HOISTING-ENGINES.

SPECIFICATION forming part of Letters Patent No. 707,851, dated August 26, 1902.

Application filed June 7, 1901. Serial No. 63,524. (No model.)

To all whom it may concern:

Be it known that I, ASHER LAMBERT, a citizen of the United States, residing at 117 Poinier street, in the city of Newark, county of Essex, 5 State of New Jersey, have invented certain new and useful Improvements in Derrick-Swinging Attachments for Hoisting-Engines, fully described and represented in the following specification and the accompanying 10 drawings, forming a part of the same.

The object of the present invention is to furnish an improved construction for the hoisting apparatus that is used in connection with a boom-derrick, so that the derrick may 15 be swung in either direction with more promptness and accuracy than is attainable by the usual means.

The invention consists of a swing drum or winch mounted to rotate in connection with 20 the hoisting-drum and connected by friction-wheels with the same gearing which rotates the hoisting-drum, such friction-wheels being arranged and operated to reverse the rotation of the swing drum or winch at pleasure.

25 Two ropes are wound in opposite directions upon the swing drum or winch and attached at their outer ends to the bull-wheel upon the derrick. The drum or winch to receive the two ropes may be combined with any ordinary

30 portable power-hoister by mounting the drum or winch in a suitable manner to be driven by the gearing of the hoisting-drum. For applying the invention to portable hoisting-machines already in existence the swing drum 35 or winch and its supporting-frame and gearing may be constructed as a separate attachment to be mounted upon the same beams or skids as the bed of the portable hoister. An ordinary hoister is provided with two parallel

40 side frames across which the drum-shafts are mounted in suitable bearings, and the swing-drum is most conveniently combined with the hoisting-drums by mounting it also upon a shaft extended across between two 45 parallel side frames, with such side frames the same distance apart as the frames of the hoister, so that they may be bolted to the same timbers or skids. The frame for the swing-drum is provided with suitable gearing

50 to connect such drum with the gearing of the hoisting-drums and to suitably reduce the speed, and one or more friction-wheels are

preferably interposed in the gearing between the hoisting-drums and swing-drum, so as to easily stop and start the swing-drum. 55

In practice when combining my improvement with existing hoisters I provide one of the hoisting-drum shafts where it overhangs its bearing with a friction-wheel and provide the gearing of the swing-drum with two friction-wheels adapted to connect with the same and arranged to turn the swing-drum respectively in opposite directions. The movement of the friction-wheels is controlled by a single hand-lever, and the ropes from the bull-wheel 65 upon the derrick are wound in opposite directions upon the swing-drum at the opposite ends of the same, so that the tension of the swinging-ropes is constantly uniform, and the stoppage or reversal of the swing-drum 70 may be completely controlled by the movement of a single lever.

The invention will be understood by reference to the annexed drawings, in which—

Figure 1 is a perspective view of a boom-derrick with the hoisting apparatus connected thereto. Fig. 2 is a plan of the hoisting apparatus with my improvements, and Fig. 3 is a side elevation of the same. Fig. 4 is a side view of the reversing-lever, showing the 75 friction-wheels and their connecting-pinions. Fig. 5 is an end view of the reversing-lever with the friction-wheels *h*' and their connecting-gears *l*'. Fig. 6 is a side view, and Fig. 7 an edge view, of the bell-crank *q*. Fig. 8 80 is a plan of the frames for the hoisting-drums and the swing-drum; and Fig. 9 is an elevation of the same, the frames being secured upon skids *T*.

a designates the post of the derrick, *b* the 90 boom, and *c* the bull-wheel upon the bottom of the post. The hoister is shown with the usual drums *d* and *d*' for hoisting the load and the boom, and the so-called "swing-drum" is designated *e* and connected by ropes *f* and 95 *f*' with the opposite edges of the bull-wheel *c*. The ropes are wound in reverse directions upon opposite ends of the drum *e*, so that the turning of the drum in any degree operates positively to turn the bull-wheel and swing 100 the boom. The drum *e* is shown connected by gear-wheels *g* and *g*' and friction-wheels *h*' and *i* with the shaft of the hoisting-drum *d*, but may be reversely connected with any

rotating shaft upon the hoister. The shaft of the drum d is shown provided with the usual overhung windlass w , formed at its inner end with a grooved friction-wheel i , and 5 a shaft k is shown mounted between the drums d and e and connected with the drum e by a pair of gears g . I have termed the wheel i a "driving friction-wheel" in the claims, and any friction-wheel connected with the 10 hoisting-drum to rotate therewith would operate with the same effect. The shaft k is provided outside of its bearing k' with a wheel g' and with a swinging lever j , which carries two interlocking pinions l , one of which 15 meshes with the wheel g' . Each of the gears l rotates upon a stud h (upon the lever-arm j) with a grooved friction-wheel h' , and a correspondingly-grooved friction-wheel is attached to the shaft of the drum d , with its 20 grooves contiguous to those of the wheel h' , so that the movement of the reversing-lever in opposite directions presses the one or the other of the grooved wheels h' into the friction-wheel i . The friction-wheels h' rotate 25 together by their connection through the pinions l , but they necessarily rotate in opposite directions, so that the motion of the gear g' can be reversed by pressing the wheels h' alternately against the wheel i . I have 30 termed the friction-wheels h' "intermediate friction-wheels" in the claims, as they transmit the power from the driving friction-wheels i to the swing drum or winch. The reverse-lever j is pivoted upon the shaft k 35 with the wheel g' , and one of the studs h is necessarily set at a greater distance from the shaft k than the other, so that only one of the pinions l meshes with and drives the wheel g' . A hand-lever m , having a latch n and notched 40 segment o to control its position, is mounted upon a shaft m' and connected by a link p and a bell-crank q with the free end of the reverse-lever and serves to hold the reverse-lever in its intermediate or neutral position, 45 in which no motion is imparted to the drum e or to press either of the friction-wheels h' against the friction-wheel i , and thus rotate the swing-drum e in either direction. In Fig. 3 the upper friction-wheel h' is shown nearer 50 to the gear-wheel g than is the lower friction-wheel and is pressed upon the wheel i , and the pinion l of such friction-wheel meshes directly with the gear-wheel g' , thus rotating the swing-drum e in the direction of the arrow e^2 . The reverse position of the lever j would throw the lower friction-wheel h' against the wheel i , and its motion would be transmitted to the gear-wheel g' through both the pinions l , thus reversing the rotation of 55 the swing-drum to the direction indicated by the arrow e^3 . The bell-crank q , which connects the link p with the reversing-lever j , is shown journaled upon the overhung end of the shaft e' , which carries the swing-drum e ; 60 but it is immaterial where the reversing-lever j or bell-crank q is pivoted, provided the operation is secured as described herein.

The operation of the friction-wheels h' and i is prompt and positive, and as the rope f unwinds in the same proportion that the rope f' 70 is wound upon the drum the ropes are kept taut and the swinging of the derrick is controlled in a positive manner. The hand-lever m for reversing the motion of the swing-drum is in practice placed contiguous to the 75 levers which control the hoisting-drums, and the entire operation of the derrick is thus controlled with perfect facility. As variations may be made in the construction of such gearing, I do not limit myself to the 80 precise construction shown in the drawings, although I have made specific claims thereto. It will be observed in Fig. 1 that the hoisting-machine frame and the appliance for swinging the derrick are secured upon skids 85 T , which hold them in their operative relation to one another and make them readily removable together.

It will be observed in Fig. 3 that the drum e and all the mechanism which connects the 90 same with the friction-wheel i are mounted upon a frame R , separate from the frame S , which carries the hoisting-drums d d' , and the appliance for swinging the boom thus constitutes a separate attachment, which may be 95 applied to any hoisting-machine by bolting it upon skids T in the proper position and furnishing the hoister with a friction-wheel i . The ordinary hoisting-machine and the swing-drum mechanism may thus be built separately and combined together where the hoisting-drum is to be used in connection with a boom-derrick, and any hoister which is 100 destitute of a swing-drum can be readily furnished with one by securing also the friction-wheel i for attachment to the hoisting-drum shaft. Such friction-wheel is readily furnished by exchanging the windlass w upon the hoister for a windlass provided with the friction-wheel, as shown in Fig. 2. Turnbuckles t are shown connected to the adjacent ends of the frames R and S to hold them 105 in their operative relation and to adjust the pressure of the friction-wheels h and h' upon the friction-wheel i . Such adjustable connection is very desirable where the swinging devices are constructed separately from the hoisting devices and are sustained upon a skid, as the bolts which fasten the two devices to the skid are liable to yield under the 110 pressure of the friction-wheels. If the swing-drum were mounted upon the same frame as the hoisting-drum, such frame would hold the parts rigidly in connection; but where the swing-drum and its frame and gearing are 115 made as a separate attachment to be connected with a hoisting-machine by fastening upon skids it is obvious that some means, like the turnbuckles, is necessary to prevent the pressure of the friction-wheels from forcing one of the frames away from the other. 120 Any means may be used which operates the same as the turnbuckles to hold the frames R and S in their operative relations. Where 125

the frame of the swing-drum is constructed to combine with the frame of the hoisting-drum upon the same timbers, it is preferable that the frames R should be constructed the same distance apart as the frames S, and I have made claim to such a construction of the frames. It is obvious that my attachment for swinging the drum is applicable to any hoister provided with drum for raising the load and actuated by a motor of any suitable kind. A steam-boiler A is shown in Fig. 1 and steam-engine cylinder B; but my invention is applicable to a hoister actuated by electric or other power. The connection of the swing-drum mechanism with the frame of the hoister by means of the turnbuckles serves to make, very readily and accurately, the adjustment which is required to operate contacting friction-wheels.

In the swinging devices heretofore connected with hoisting-machines the gearing for the swing-drum has been connected permanently with the gearing of the other drums, so as to run continuously, thus involving great wear of such parts. In my construction all the gearing for the swing-drum is disconnected from the gearing of the hoisting-drums when the swing-drum is not in use, and the friction-gearing and the gears g and g' are then wholly preserved from wear. A winch w' is shown overhung upon the shaft of the hoisting-drum d' , and both the winches w and w' can thus be kept in continuous motion and utilized at any moment without the slightest interference from the attachment which constitutes the swinging device.

It is obvious that a winch which is overhung from its bearings can be used with two ropes wound in opposite directions and connected to a bull-wheel to swing the derrick in the desired manner, provided such winch is connected with the hoisting-drum by gearing which rotates it at a slower speed than such drum and which is provided with friction-wheels to reverse the motion by the manipulation of a single hand-lever. My invention is shown herein in a convenient form for application as a separate attachment to hoisting-machines; but the rotation of the swing-drum or winch at a speed below that of the hoisting-drum and the use of the two ropes and friction-gearing in the manner described constitute the essence of the invention, which may therefore be carried out without the use of the precise construction herein described.

Having thus set forth the nature of the invention, what is claimed herein is—

1. In a hoister, the combination, with a hoisting-drum, of the means for swinging a boom-derrick, consisting of the swing-drum e having the swing-ropes f , f' wound thereon in reverse directions, a friction-wheel upon the shaft of the hoisting-drum, a lever pivoted upon the frame of the hoister, two friction-wheels geared together and mounted upon such lever, and suitable gearing con-

nected one of such friction-wheels with the swing-drum.

2. The combination, with a hoisting-drum and drum-shaft, and a grooved friction-wheel i upon said drum-shaft, of a swing-drum journaled adjacent to the hoisting-drum and having the swing-ropes f , f' wound thereon in reverse directions, the shaft k journaled between the hoisting-drum and swing-drum and a pair of gear-wheels connecting such shaft with the swing-drum, the cog-wheel g' and reverse-lever j upon the shaft k , the friction-wheels h' pivoted upon the reverse-lever, 80 pinions l connecting such friction-wheels, one of such pinions engaging the gear-wheel g' , and means for operating the reverse-lever to press the friction-wheels at pleasure upon the wheel i .

3. The combination, with a hoisting-drum and drum-shaft, and a grooved friction-wheel i upon said drum-shaft, of a swing-drum journaled adjacent to the hoisting-drum and having the swing-ropes f , f' wound thereon in reverse directions, the shaft k journaled between the hoisting-drum and swing-drum, a pair of gear-wheels connecting shaft k with the swing-drum, the cog-wheel g' and reverse-lever j upon the shaft k , the friction-wheels h' pivoted upon the reverse-lever and the pinions l connected therewith, the gear-wheel g' having one of such pinions engaged therewith, the bell-crank q upon the drum-shaft e with pin engaging the reverse-lever, the shaft m' , the link p connecting the shaft m' with the bell-crank, and the latch n and segment o for adjusting and securing such shaft, the whole arranged and operated substantially as herein set forth.

4. The attachment for hoisters having a hoisting-drum provided with the friction-wheel i , comprising the frames R, the drum e and shaft k journaled thereon, a pair of gear-wheels connecting the drum and the shaft k , the gear-wheel g' and the reverse-lever j upon said shaft k outside of the frame, the friction-wheels h' pivoted upon the reverse-lever, the pinions l connecting said friction-wheels, and one of such pinions engaging the gear-wheel g' , and means mounted upon the frame R for actuating the reversing-lever, as and for the purpose set forth.

5. The combination, with the hoister having the parallel frames S, a shaft extended across the same, a hoisting-drum upon such shaft, and gearing to drive such drum, of the detachable swing-drum attachment comprising the frames R set at the same distance apart as the frames S to be bolted upon the same timbers or skids, the shaft e' extended between the frames R and having the swing-drum e mounted thereon, a train of gearing connecting the hoisting-drum with the swing-drum and adapted to reduce the speed of the swing-drum, and a reversing-lever to reverse the swing-drum as required, the attachment being constructed separately and adapted for application to such hoisters when first manu-

factured or after they have been erected and used, substantially as herein set forth.

6. The combination, with a hoisting-drum, of the means for swinging a boom-derrick, 5 consisting of a swing drum or winch having swinging ropes wound thereon in reverse directions, a driving friction-wheel suitably connected to the hoisting-drum to be revolved therewith, and a lever carrying two intermediate friction-wheels geared together to be 10 pressed at pleasure upon the driving friction-wheel, and one of the intermediate friction-

wheels connected by suitable gearing to the swing drum or winch, to rotate the same at pleasure in opposite directions, or to wholly 15 disconnect the same from the hoisting-drum.

In testimony whereof I have hereunto set my hand in the presence of two subscribing witnesses.

ASHER LAMBERT.
